TELEVISION ANTENNA ASSEMBLY

John Paul Jones, Jr., Pottstown, Pa., assignor to
 Philco Corporation, Philadelphia, Pa., a corpora-
 tion of Pennsylvania

Application January 3, 1950, Serial No. 136,548

1 Claim. (Cl. 250—33)

1

The invention herein described and claimed relates to an improved antenna assembly for television receivers.

Present television receivers are required to receive signals in two non-contiguous high-frequency bands one of which (the lower band) extends from 54 to 88 megacycles and includes channels Nos. 2 through 6 and the other of which (the upper band) extends from 174 to 216 megacycles and includes channels Nos. 7 through 13.

In some areas a single dipole may be satisfactory for the reception of signals in both bands, but in many areas two separate dipoles are advantageously employed, one for the low-band and the other for the high-band channels.

The present invention relates particularly to an antenna assembly comprising a high-band dipole, a low-band dipole, a stub interconnecting the high-band and low-band dipoles, and a single or common twin-lead transmission line connecting both dipoles to the television receiver.

I have found that the overall effectiveness of the above antenna assembly may be increased very substantially by connecting a small, mechanically rigid, loop inductor across the terminals of the high-band dipole. When this is done, the effectiveness of the assembly compares very favorably with that of an antenna assembly comprising a plurality of folded dipoles each of which is cut to the individual requirement of a particular channel and each of which is connected to the television receiver by a separate twin-lead transmission line. Such an arrangement is, of course, too complex to be commercially practical, but it provides an excellent reference for purposes of comparison since a folded dipole of such length as to be naturally resonant to the frequency of the individual channel would provide very satisfactory reception on that channel, assuming a 300-ohm twin-lead transmission line to be employed, as is ordinarily the case.

The theory underlying the improvement which the addition of the small loop inductor effects is not simple, and is complicated by the fact that we are dealing with a relatively wide range of frequencies (54 to 216 megacycles). The length of the stub which interconnects the high-band and low-band dipoles is conventionally made about one-half wavelength at the center frequency of the high band. This is done in order that the low-band dipole may be connected to the transmission line at or near a voltage node with respect to the high-band frequencies. Unfortunately, a stub equal to one-half wavelength at

the center frequency of the high band closely approaches one-quarter wavelength at the low-band frequencies, particularly at the frequencies near the upper edge of the low band. At least some of the low-band channels will, therefore, see a low-impedance one-quarter wavelength open line when looking at the high-band dipole from the terminals of the low-band dipole. It has been found, experimentally, that the low-band channel which is attenuated the most is that channel whose one-quarter wavelength equals the length of the stub plus the length of one arm of the high-band dipole. The addition of the small loop inductor across the terminals of the high-band dipole, as proposed by the present invention, effectively changes the impedance seen by the low-band channels from a low-impedance one-quarter wavelength open line to a high-impedance one-quarter wavelength shorted line, thus improving very substantially the low-band channels. To avoid attenuating the high-band channels, the loop inductor is made large enough to present a reasonably high impedance (about 250 ohms) to the high-band frequencies as seen from the terminals of the loop. Thus, the high-band channels are not adversely affected by the addition of the loop inductor.

It is a primary object of the present invention to provide, for a television receiver required to receive signals in two non-continuous high-frequency bands, an antenna assembly of relatively simple construction capable nevertheless of operating as effectively as the more complex assembly of a plurality of individual dipoles each naturally resonant to one of the channels involved.

Another object of the present invention is to provide means for improving the efficiency of a two-band antenna assembly comprising a high-band dipole, a low-band dipole, a stub interconnecting the two dipoles, and a single parallel-lead transmission line connecting both dipoles to the television receiver.

These and other objects, advantages and features of the present invention will be best understood from a consideration of the following detailed description and accompanying drawing wherein:

Figure 1 shows the loop inductor of the present invention incorporated into an antenna assembly comprising a plain high-band dipole and a plain low-band dipole mounted on a common mast, one above the other;

Figure 2 shows the loop inductor of the present

invention incorporated into an antenna assembly comprising a plain high-band dipole, a plain low-band dipole and a reflector mounted on a common mast, all in the same horizontal plane;

Figure 3 is a graph indicating the relative effectiveness of antenna assemblies in which the loop inductor of the present invention is incorporated;

Figures 4 and 5 show the new loop inductor embodied in antenna assemblies employing reflectors; and

Figure 6 shows the construction of new loop inductor in detail.

Referring now to Figure 1, the antenna assembly there shown includes a high-band dipole 10 mounted at or near the top of mast 11, a low-band dipole 12 mounted on mast 11 below the high-band dipole 10, a stud 14 interconnecting the terminals of the high-band and low-band dipoles, and a transmission line 15 extending from the terminals of the low-band dipole 12 to the television receiver (not shown).

Dipole 10 preferably has a length equivalent to one-half wavelength at the center frequency of the high band.

Stub 14 which interconnects the high-band and low-band dipoles is preferably a section of 200-ohm heavy-duty twin-lead having a length equivalent to one-half wavelength at the center frequency of the high band. Thus, low-band dipole 12 is connected at or near a voltage node with respect to the high-band frequencies.

Transmission line 15, which extends from the terminals of low-band dipole 12 to the television receiver (not shown), is conventionally a length of parallel-wire or twin-lead having a characteristic impedance of 300 ohms.

In accordance with my invention, a small inductor 17 of predetermined configuration and dimensions is connected across the terminals of high-band dipole 10 in the manner shown in Figure 1. In the preferred embodiment, inductor 17 comprises a C-shaped length of conductive material terminating at the ends in lugs 18, 19, as clearly shown in Figure 6. While the inductor may be formed of any material having good conductive properties, it is preferably formed of aluminum wire having a diameter of the order of one-eighth inch. The diameter of the C-shaped loop is about three and one-quarter inches, which is equivalent to about one-eighteenth wavelength at the center-frequency of the high band, and the total length of the inductor, from lug center to lug center is about nine and one-half inches, which is equivalent to about one-sixth wavelength at the center-frequency of the high band. The inductor is very readily installed, as by means of a couple of bolts and nuts, and is sufficiently rigid to withstand bending by the wind.

In Figure 2, the high-band dipole 10 and low-band dipole 12 are secured to a spacer bar 20 and disposed in a common horizontal plane. The two dipoles are separated in space by one-quarter wavelength at the center-frequency of the high band in order that low-band dipole 12 may function as a reflector for high-band dipole 10. Stub 14, however, has the same length as it has in Figure 1, namely, one-half wavelength at the center-frequency of the high band. Thus, low-band dipole 12 is connected at a voltage node with respect to high-band frequencies. The C-shaped loop inductor 17 is connected across the terminal of high-band dipole 10, in the same manner as in Figure 1. A reflector bar 21 is provided for low-band dipole 12, the spacing therebetween be-

ing one-quarter wavelength at one of the mid low-band frequencies.

I have found that the addition of the loop inductor 17 to the antenna assembly shown in Figure 2 effects a very material improvement in the operating efficiency of the antenna assembly, particularly at the low-band frequencies.

In Figure 4, the loop inductor 17 is shown employed in an antenna assembly in which high-band dipole 10 and low-band dipole 12 are each provided with a reflector, identified by numerals 40 and 42 respectively. Stub 14 has a length equivalent to one-half wavelength at the center-frequency of the high band, as in Figures 1 and 2.

In Figure 5, a folded dipole 50 is substituted for the plain high-band dipole 10 shown in Figure 4.

In Figure 3 I have plotted a graph to show the relative effectiveness of my improved antenna assembly. In Figure 3, one hundred per cent efficiency corresponds to the results obtained from a folded dipole cut to proper length for the particular channel. The curves A correspond to the results obtained from an antenna assembly similar to that shown in Figure 1 comprising a plain high-band dipole, a loop inductor connected across the terminals of the high-band dipole, a plain low-band dipole, a stub (having a length equivalent to one-half wavelength at the mid high-band frequency) interconnecting the high-band and low-band dipoles, and a single twin-lead transmission line. The curves B correspond to the results obtained from an antenna assembly similar to that shown in Figure 4, i. e. having a high-band reflector and a low-band reflector (in addition to components similar to those just described in connection with Figure 1).

It will be observed from the curves shown in Figure 3 that the operating efficiencies of my improved antenna assemblies compare very favorably with those of an assembly wherein an individual folded dipole is provided for each channel. If, however, the C-shaped loop inductor is removed, the efficiency of the two-band dipole antenna assembly drops very materially at the low-band channels.

It will also be observed from curves A and B of Figure 3 that the response of my improved antenna assembly (both with and without reflectors) is fairly flat over the entire range of low-band and high-band frequencies. The flatness of the response over the low band was obtained by cutting the low-band dipole to channel No. 3 after determining that stub 14 and loop inductor 17 were together equivalent to a one-quarter wavelength closed line at channel No. 5. By so doing, the flatness of the response over the low-band frequencies was improved over that which would have been obtained had the low-band dipole been cut to the same frequency with respect to which stub 14 and inductor 17 represented a one-quarter wavelength closed line.

Having described my invention, I claim:

A two-band high-frequency antenna assembly comprising: a first dipole naturally resonant at a frequency substantially midway between the end frequencies of the high band; a second dipole naturally resonant at a frequency about midway between the low-band center-frequency and the lower end-frequency of the low band; a stub interconnecting the terminals of said first and second dipoles, said stub having a selected length equal to one-half wavelength at the center-frequency of the high band, which is also about one-quarter wavelength at a frequency near the up-

per end of the low band; a common transmission line connecting both said dipoles to signal utilization means, said transmission line being connected to the terminals of said second dipole directly and to the terminals of said first dipole by way of said stub; and an inductor connected across the terminals of said first dipole, said inductor comprising a C-shaped loop of mechanically rigid conductive material having a loop diameter of approximately one-eighteenth wavelength at the center-frequency of the high band and a conductor length of approximately one-sixth wavelength at the center-frequency of the high band, said C-shaped loop inductor and said stub together being equivalent to a one-quarter

10

wavelength shorted line at a low-band frequency about midway between the low-band center frequency and the upper end-frequency of the low band.
